(74) **Primary Examiner** — Anhdao Doan
Attorney, Agent, or Firm — Nicole J. Einerson**CLAIM**

The ornamental design for a rotatable sample processing disk, as shown and described.

DESCRIPTION

FIG. 1 is a top perspective view of a rotatable sample processing disk, showing the new design;
 FIG. 2 is a bottom perspective view thereof;
 FIG. 3 is a top plan view thereof;
 FIG. 4 is a bottom plan view thereof, and;
 FIG. 5 is a side elevational view thereof.
